UNITED STATES PATENT OFFICE.

FROST V. SIMPSON, OF MILWAUKEE, WISCONSIN, ASSIGNOR TO KIECKHEFER BOX COMPANY, OF MILWAUKEE, WISCONSIN, A CORPORATION OF WISCONSIN.

PLATEN CONNECTION.

1,228,978.

Specification of Letters Patent.

Patented June 5, 1917.

Application filed October 28, 1914. Serial No. 863,938.

To all whom it may concern:

Be it known that I, FROST V. SIMPSON, a citizen of the United States, and resident of Milwaukee, in the county of Milwaukee and State of Wisconsin, have invented new and useful Improvements in Platen-Connections, of which the following is a description, reference being had to the accompanying drawings, which are a part of this specification.

This invention has for its object to provide a rocking platen connection for box presses and the like such as the press for clamping the flaps of a paper or fiber box shown in my co-pending application for Letters Patent Serial No. 847,819 filed June 29th, 1914, which will permit of the platen rocking in any direction to adapt itself to an uneven thickness in the fiber board and assure an even pressure throughout the surfaces of the box blank which are being glued together.

A box press of this character having a rigidly mounted platen may be incapable of applying sufficient pressure to the glued flaps at one end of the box if the flaps at the other end of the box are thicker and to equalize the pressure against all of the sealing flaps of the box when the stock from which the box is made is of uneven thickness the platen under the present invention is so mounted as to be capable of tilting to one side or the other or to the front or rear.

With the above and other objects in view the invention consists in the platen connection as herein claimed and all equivalents.

Referring to the accompanying drawings in which like characters of reference indicate the same parts in different views:

Figure 1 is an end elevation of a press for clamping the flaps of paper or fiber boxes having a platen connection constructed in accordance with this invention;

Fig. 2 is an enlarged detailed sectional side view of the platen connection with the platen in a horizontal position;

Fig. 3 is a similar view with the platen tilted to the rear;

Fig. 4 is a similar view with the platen tilted to the front; and

Fig. 5 is a similar view with the platen tilted to the left.

In these drawings the press is shown as comprising a vertically movable plunger 14

slidably mounted on a stationary support 11 and operated by a suitable cam lever 17 and coöperating with a platen 24 carried on the upper end of a swinging platen stem 23 all as described in the application referred to.

The present invention has relation to the particular means for fastening the platen 24 to the upper end of the swinging stem 23. The upper end of the tubular stem 23 is reduced in diameter so as to have ample play within the socket 30 on the bottom of the metal platen 24. A thumb screw 31 is threaded through the socket 30 and has a reduced end 32 to loosely fit within one of a number of openings 33 formed in such reduced end of the stem 23 according to the threaded adjustment of the stem 23 in its pivotally mounted socket 22. The stem 23 does not bear at its upper end against the bottom of the platen 24, but supports the platen by means of thumb screw 31 so that the platen is free to rock in any direction as permitted by the play of the end of the tubular stem in the socket 30 and as permitted by the play of the end of the thumb screw in the opening 33.

By means of this platen connection the platen while retaining an approximately fixed position on the swinging stem is capable of a slight movement in any direction to adapt itself to a variation in thickness of the fiber box flaps when such box 28 is placed thereon with its bottom forming flaps treated with an adhesive folded together upon the platen and the plunger 14 is moved downwardly by the action of the cam lever 17. Thus an even pressure is brought to bear upon the flaps of the box notwithstanding a difference in thickness thereof so that when the press is opened after the adhesive has set all flaps will be securely glued together.

The platen stem 23 is shown mounted in the socket 22 and this structure is pivoted upon the pin 34. This pin 34 is carried in the foot or base plate 35 upon which the whole device stands. The socket 22 has a rearwardly extending bracket 36 carrying an adjusting screw, and also has a forwardly extending toe 38. In the normal alined position of the platens 24 and 14 as shown in Fig. 1, the socket is carried by the pin 34 and the adjustment screw 37. When it is desired to insert or remove a box 28, then the stem 116

23 and the socket 22 are swung clockwise about the pin 34 until the toe 38 engages the base plate 35. In this position the platens 24 and 14 are disaligned and the box with its 5 one end sealed may be removed and another which it is desired to seal put in its place. Thereupon the stem 23 is swung counter-clockwise to again align the plunger so that the box flaps which have been provided with 10 paste may be sealed together.

What I claim as new and desire to secure by Letters Patent is:

1. A press for sealing flaps of paper boxes and the like having a suitably operated 15 plunger, a platen stem, a platen opposed to the plunger and having a socket loosely mounted on the end of the platen stem, means for bringing said platen and said plunger into and out of parallel aligned relation, and a pin projecting into the interior 20 of the socket and loosely entering an opening near the end of the stem to permit the platen to tilt and adapt itself to a variation in thickness of the material operated upon.
- 25 2. A press for sealing flaps of paper boxes and the like, comprising a suitably operated plunger, a pivotally mounted socket, a platen

stem adjustably threaded in the socket, a platen opposed to the plunger and provided with a socket loosely mounted on the end of the platen stem, there being openings in the platen stem near the end thereof, and a thumb screw threaded in the socket of the platen and engaging one or another of the 30 openings of the platen stem according to the 35 threaded adjustment of the platen stem and permitting the platen to tilt in any direction to accommodate itself to a variation in thickness of the box flaps.

3. A device for sealing the flaps of fiber 40 boxes and the like, comprising two platens, means for moving said platens into and out of parallel aligned relation, yielding means for moving said platens toward each other when aligned, and a universal mounting for 45 one of said platens so that pressures may be substantially equally exerted throughout the area of said platens.

In testimony whereof, I affix my signature, in presence of two witnesses.

FROST V. SIMPSON.
